Primary Examiner — John A Voytek(74) *Attorney, Agent, or Firm* — Carter, Deluca & Farrell LLP(57) **CLAIM**

The ornamental design for a faucet, as shown and described.

DESCRIPTION

FIG. 1 is a front perspective view of a faucet in accordance with the present design;

FIG. 2 is a front elevational view thereof;

FIG. 3 is a rear elevational view thereof;

FIG. 4 is a right side elevational view thereof;

FIG. 5 is a left side elevational thereof;

FIG. 6 is a top plan view thereof;

FIG. 7 is a bottom plan view thereof; and,

FIG. 8 is a perspective view of the faucet shown with a sprayer of the faucet in a pulled down configuration.

The broken lines shown are included for the purpose of illustrating a portion of the faucet that form no part of the claimed design.
